UNITED STATES PATENT OFFICE.

JOHN AGAR, OF EAST ORANGE, NEW JERSEY.

SMOOTHING-IRON FOR HATS.

SPECIFICATION forming part of Letters Patent No. 635,633, dated October 24, 1899.

Application filed January 18, 1899. Serial No. 702,503. (No model.)

To all whom it may concern:

Be it known that I, JOHN AGAR, a citizen of the United States, residing at East Orange, in the county of Essex and State of New Jersey, have invented certain new and useful Improvements in Smoothing-Irons for Hats, &c.; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has for its objects to facilitate the operation of ironing hats or other articles of apparel, &c., when arranged upon a block having convex or concave surfaces, to obtain a more uniform and perfect finish to the ironed surface, and to secure other advantages and results, some of which may be referred to hereinafter in connection with the description of the working parts.

The invention is particularly useful in connection with machines for ironing hat-bodies, represented by the one shown in Patent No. 420,961, of February 11, 1890, although it is evident that the invention may be employed with other machines and in other relations.

The invention consists in the improved smoothing-iron and in the arrangements and combinations of parts thereof, all substantially as will be hereinafter set forth, and finally embraced in the clauses of the claim.

Referring to the accompanying drawings, in which like letters of reference indicate corresponding parts in each of the views, Figure 1 is a plan of the improved smoothing-iron disconnected from an inclosing casing. Fig. 2 is a side view of the same, and Fig. 3 is a section taken at line *x*. Fig. 4 is a side elevation showing the device inclosed and in a condition to be constantly kept hot. Fig. 5 is a section on line *y*, and Fig. 6 is a section at line *z*.

In said drawings, *a a a* indicate the ironing blocks or sections. These are provided at their opposite ends with perforated tongues *a' a'*, which latter are disposed central or in the longitudinal axis of the sections, as shown in Figs. 1 and 6. The said blocks or sections lie side by side in series, the tongues of con-

tiguous sections forming recesses between adapted to receive the tongues of the next series of sections. Thus the sections are arranged in a series of series and are loosely pivoted together by means of flexible pivots *b*. Said flexible pivots are loosely arranged in the perforations of the tongues, so that the said tongues will have more or less freedom of action thereon not only pivotally, but also laterally, so that each section will be permitted to assume a position of close contact with the irregular surface of the fabric immediately beneath and accommodate itself to the variations of the curves as the hat-block changes its position because of the rotation thereof in the machine.

The pivots connecting one series of ironing-sections with the next series in order are preferably of a linked chain, although other flexible pivotal connections may be employed, such as a flexible wire, rope, cord, or the like.

At one end of the ironing-sections I may employ a wire handle or bail *c*, by means of which the said smoothing-iron may be suspended close to the rotary hat-block of the machine, the said bail holding the end of the iron approximately in a desired plane or line and also serving to enable the said iron to be manipulated or carried from place to place. An eye *c'* may be provided in the bail to enable the same to be fastened within the machine in which it is employed. A similar bail or handle *c'* is or may be arranged at the opposite end of the said iron, adapted to receive a weight or spring to increase the pressure of the iron upon the article ironed.

The said smoothing-iron may be heated in any suitable manner—for example, the heating operation may be effected either while the iron is on the machine by means of electricity, gas, or the like, or the iron may be independently heated by being placed upon a stove or other heating-surface, and in this latter event the heating-surface or stove may be especially adapted for heating purposes and may be of cylindrical or curved shape.

While I refer to the sections as "irons," it is very evident that the sections may be made of any suitable metal, such as brass or the like.

While I show the smoothing-iron in the drawings in four series of sections, it is evi-

dent that the said iron may include a greater number of series, and in each series the number of sections may be multiplied or reduced in number. Furthermore, it is quite evident 5 that the shape of the sections may be varied to meet varying conditions.

In connection with the sectional smoothing-iron I prefer to employ a box or closure *e* of heavy cast metal, the said closure being made 10 hollow to receive a quantity or number of metallic balls *f*, adapted to press down upon the upper side of the ironing-sections, and thus force the latter with considerable pressure against the fabric ironed. The under side 15 of the said box is open to receive the collection of ironing-sections *a a a*, the end sections of which latter are closely pivoted at the front and rear ends of the box, as at *g*, so that the said sections will not be prevented 20 from conforming to the irregular sections, as hereinbefore described. The sides of the box are to some extent open near their lower edges, and thus the said ironing-blocks *a a a* will also be permitted to assume their 25 positions without interference therewith.

The side openings are guarded by a series of linked side pieces *h h h*, the said links being loosely connected, so as to be free to assume the desired positions without interfering 30 with the ironing operations. The box is provided with perforated, heating-pipes *i i*, adapted to supply a mixture of inflammable gas and air to the interior of the box or case, whereby the flame may be maintained by 35 which the box and iron are kept at a high temperature. The irons thus inclosed may be linked or connected to the machine by any suitable means. The balls *f* within the box not only serve as weights to secure the desired pressure, but diffuse the heat and guard 40 the ironing-sections against a direct flame and prevent the latter from passing through the joints into contact with the hat or fabric ironed.

45 Having thus described the invention, what I claim as new is—

1. As an article of manufacture, a sectional smoothing-iron, comprising blocks having substantially plane under surfaces, said sections or blocks being connected together and 50 free of one another to accommodate themselves to curved or irregular surfaces, substantially as set forth.

2. As an article of manufacture, a smoothing-iron comprising a series of flat-faced ironing-blocks connected together by flexible pivots, substantially as set forth. 55

3. The improved smoothing-iron comprising a series of series of ironing-sections pivotally connected and forming a continuous 60 smooth under surface, substantially as set forth.

4. The improved smoothing-iron comprising a series of series of ironing-sections having smooth under surfaces, each section of 65 which is provided at its opposite ends with tongues which are perforated and receive pivotal connections, substantially as set forth.

5. The combination with the sectional smoothing-iron of a closure and heating-pipes, 70 substantially as set forth.

6. The improved smoothing-iron, comprising a metal box open at one side, a series of series of smoothing blocks or sections loosely pivoted to one another and to said box, and 75 means for supplying the box with an inflammable gas, substantially as set forth.

7. The combination of the closure, sectional smoothing-iron, balls, and heating means, 80 substantially as set forth.

8. The combination of the box or closure open at one side and having a collection of loosely-connected ironing-sections arranged across the opening, and means for heating the sections, substantially as set forth. 85

In testimony that I claim the foregoing I have hereunto set my hand this 15th day of December, 1898.

JOHN AGAR.
